UNITED STATES PATENT OFFICE

2,472,763

AIRPLANE

Jack F. Rodeck, Odessa, Wash.

Application August 5, 1946, Serial No. 688,434

7 Claims. (Cl. 244—13)

1

My present invention relates to an improved airplane and especially to the novel and unique controls used in conjunction with the improved shape to produce a heavier-than-air craft adapted to offset and overcome the supersonic limitations and to offer a craft easier to handle and maneuver under all flying conditions.

In the accompanying drawings I have illustrated one complete example of the physical embodiment of my invention according to the best mode I have thus far devised but it will be understood that various changes and alterations may be made in the exemplified structure within the scope of the appended claims.

In the drawings:

Figure 1 is a top plan view of the airplane of my invention.

Figure 2 is a perspective view thereof.

Figure 3 is a front elevational view.

Figure 4 is a partial top plan of a wing.

Figure 5 is a detail view in section of the control for the expansible wing.

Figure 6 is a longitudinal vertical sectional view of the wing in contracted position.

Figure 7 is a longitudinal vertical sectional view of the wing in expanded position.

Figures 8, 9, 10 and 11 are rear elevational views showing the rudder flaps in various combined positions to enhance the control.

Referring now to the drawings wherein I have illustrated the preferred form of the present embodiment of my invention, I employ a cockpit 2 terminating forwardly of the wings and rearwardly merging into the fuselage of spaced upper and lower rearwardly extending vertical fins 4—5 which tapers rearwardly as at 6.

The wings 8 and 10 extend from the approximate mid point of the cockpit substantially the full length of the fuselage and are formed with recesses 12—14 forming an open center.

The propeller 16 is secured rearward of the cockpit and in the open center and while I have shown the propulsion means to be a blade propeller it will be apparent that a jet at 17 may well be employed in lieu thereof.

Extending along a substantial portion of the side edges of the wings 8 and 10, I have provided control flaps 18 hinged longitudinally of the ship as at 20 and these flaps may be controlled by suitable means from the cockpit.

Struts 22 strengthen and brace the wings and in order to vary the slip-streamed leading edge of the wings under proper conditions I have formed these wings with hinged sections 24 secured by springs 26. Within the containers 28

2

and 30 forming a box I provide an expansible bag 32 as rubber and this bag may be inflated to pivot the spring retained hinged section in take-off and landing and other slow speed operations. The bag is inflated automatically and expands between the walls 34 and 36 to fill the space therebetween, from air under pressure in pipe 38 having relief valve 40. Relief valve 40 is provided with a minute escape port, and when air pressure supply is shut off by control valve 42, the pressure in bag 32 is gradually reduced until relief valve 40 opens under spring tension, to exhaust the balance of air from bag 32. The control valve 42 is formed with a seat 43 and the impeller 44 is rotatably secured upon the shaft valve 45 to close the valve when the speed of the impeller reaches a predetermined point. Conversely as in landing as the impeller speed decelerates, the valve will open to permit air under pressure from tank 46 to pass therethrough.

Brake flaps 48 are positioned under the wings 8 and 10 controllable from the cockpit and the rear ailerons 50 may be raised or lowered by suitable means.

In a diamond shaped frame 51 between the wings and the upper and lower fuselage sections 4 and 5, I employ the rudder flaps 52, 54, 56 and 58 independently controlled from the cockpit.

In figures 8 through 11, I have shown various combined positions to effect added control to the ship and, of course, many other combinations thereof with the brake flaps 48 and the ailerons 50 may be employed.

With all of the flaps in parallel position with regard to the frame, the flaps form a Venturi tube at the rear of the open center of the wings and the blast from the propulsion means will be restricted in its passage therethrough adding to the propulsion force.

The control flaps 18 prevent the outward and upward air pressure from curling over the wing edges and also increase the maneuverability of the ship in taking off or landing in a cross wind.

By locating the propeller amidships, I have offset at the turbulence point the so-called second shock wave encountered at supersonic speeds and the propeller destroys this shock wave.

Further with the wings receding toward the outer edges as shown, the tips clear the first shock wave and avoid compression and vibrations encountered at supersonic speeds.

The longitudinal supersonic wing design is constructed in its profile outline so that it will have the highest approach towards combating the supersonic disturbances. A slim and sharp edged

airfoil design is employed for this purpose, yet, it maintains its strength through the decrease of mechanical leverage by adopting the smaller aspect ratio.

The lift properties for the small aspect ratio and low speed operations are compensated by the lift co-efficient stabilizer comprising the pneumatic tube along the leading edge of the wing. When inflated, the wing will have a greater lift co-efficient and as sufficient speeds are reached automatic deflation will occur.

Having thus fully described my invention what I claim as new and desire to secure by Letters Patent is:

1. In an airplane the combination with a fuselage having spaced upper and lower rearwardly extending vertical fins, and wings extending substantially the full length of the fuselage and centrally recessed to form with the spaced fins an open center, of propulsion means located forwardly in the open center, an open frame connecting the aft end of the wings and fins and aligned to permit the passage of the propulsion blast therethrough, and rudder flaps on the frame independently controlled to maneuver the airplane.

2. In an airplane the combination with a fuselage having spaced upper and lower rearwardly extending vertical fins, and wings extending substantially the full length of the fuselage and centrally recessed to form with the spaced fins an open center, of propulsion means located forwardly in the open center, a diamond-shaped open frame connecting the aft end of the wings and fins and aligned to permit the passage of the propulsion blast therethrough, and rudder flaps on the frame independently controlled to reduce the opening through the frame to maneuver the airplane.

3. In an airplane the combination with a fuselage having spaced upper and lower rearwardly extending vertical fins, and wings extending substantially the full length of the fuselage and centrally recessed to form with the spaced fins an open center, of propulsion means in the open center, rudder flaps disposed rearwardly about the open center, and hinged sections for the leading wing edges, and pneumatic means for pivoting the section to vary the lift co-efficient.

4. In an airplane the combination with a fuselage having spaced upper and lower rearwardly extending vertical fins, and wings extending substantially the full length of the fuselage and centrally recessed to form with the spaced fins an open center, of propulsion means in the open center, rudder flaps disposed rearwardly about the open center, hinged sections for the leading wing edges, a sectional container within the wing, an inflatable bag in the container, and air speed controlled means for inflating the bag.

5. In an airplane the combination with a fuselage having spaced upper and lower rearwardly extending vertical fins, and wings extending sub-

stantially the full length of the fuselage and centrally recessed to form with the spaced fins an open center, of propulsion means in the open center, rudder flaps disposed rearwardly about the open center, hinged sections for the leading wing edges, a sectional container within the wing, an inflatable bag in the container, and impeller controlled means for inflating the bag to pivot the section.

6. In an airplane the combination with a fuselage having spaced upper and lower rearwardly extending vertical fins, and wings extending substantially the full length of the fuselage and centrally recessed to form with the spaced fins an open center, of propulsion means in the open center, rudder flaps disposed rearwardly about the open center, hinged sections for the leading wing edges, a sectional container having walls extending to the edge of the wing, an inflatable bag in the container expandable upon distension of the sections of the container between the walls to fill the space therebetween, impeller controlled means for inflating the bag to pivot the wing section, and a relief valve for the inflated bag.

7. In an airplane the combination with a fuselage having spaced upper and lower rearwardly extending vertical fins, and wings extending substantially the full length of the fuselage and centrally recessed to form with the spaced fins an open center, of propulsion means located forwardly in the open center, an open frame connecting the aft end of the wings and fins and aligned to permit the passage of the propulsion blast therethrough, rudder flaps on the frame independently controlled, brake flaps on the under side of the wings, hinged sections for the leading wing edges, a sectional container having walls extending to the edge of the wing, an inflatable bag in the container expandable upon distension of the sections of the container between the walls to fill the space therebetween, a pressure tank and communicating means between the tank and the bag, and a valve in said means responsive to air speed and including an impeller to actuate the valve to open position when the air speed reaches a predetermined point in deceleration.
